A. WILD

PORTRABLE ELECTRIC STAND LAMP

Filed Sept. 16, 1925

FIG. 1

FIG. 2

UNITED STATES PATENT OFFICE.

ALBERT WILD, OF BROOKLYN, NEW YORK.

PORTABLE ELECTRIC STAND LAMP.

Application filed September 16, 1925. Serial No. 56,582.

This invention relates to improvements in portable, self-contained electric lamps comprising an interchangeable battery in its foot part, and it is the principal object of 5 the invention to provide the lamp stand near its foot part with a rotatable sleeve or ring for closing or breaking the lamp circuit.

Another object of the invention is the provision of a portable battery lamp equipped 10 with means for allowing a dimming of the light.

A further object of the invention is the provision of a lamp of this type of simple and inexpensive construction, yet durable 15 and efficient.

These and other objects and advantages of the invention will become more fully known as the description thereof proceeds, and will then be specifically defined in the 20 appended claims.

In the accompanying drawing, forming a material part of this disclosure:

Fig. 1 is a front elevation of a lamp constructed according to the present invention.

Fig. 2 is a longitudinal sectional view 25 thereof.

Fig. 3 is a bottom plan view of the lamp foot after the removal of the battery, showing the lamp cut out.

Fig. 4 is a similar view with the battery 30 in place and the lamp cut in.

Fig. 5 is a detail view of the lamp dimmer.

The lamp according to the present invention comprises a foot part consisting of an outer shell 10 and an inner insulated housing 11 in said shell carrying at its upper end the stand 12 equipped at its upper end with the usual socket 13 for the reception of the lamp 14 and carrying the removable shade 40 15.

Within the foot part 11 the springs 16 for securing the dry battery 17 are arranged, and the contacts 18.

Near its lower end the stand is surrounded 45 by a short, rotatable sleeve or ring 19 having at its lower end two oppositely disposed depending flanges 20, 21 extending into the lamp foot. To the flange 21 a pin 22 is secured adapted to contact upon the rotation 50 of the sleeve 19 with a metal strip 23 connected to or made integrally with the foot contact 18.

A wire or cord 24 is attached at one end to pin 22, while its other end is attached by

means of a screw 25 to the socket of the 55 lamp 14.

In order to limit the rotation of sleeve 19, one of the flanges, 20, is equipped with a notch 26 adapted to be engaged by a metal strip 27 or the like, upon the engagement between pin 22 and strip 23 (Figures 3 and 4).

In the position of the sleeve 19, illustrated in Figure 4, the current from battery 17 is lead to the lamp by means of the wire 24, and the lamp will start to glow, while upon 65 the rotation of the sleeve 19 in the opposite direction, the circuit will be interrupted by the disengagement of pin 21 from the metal strip 23.

In order to allow a dimming of the light, 70 a resistance 28 is provided within the lamp stand 12 and is connected by means of a wire 29 to a suitable switch 30 allowing a cutting in or out of circuit of the resistance.

It will be understood, that I have disclosed 75 herein as an example the preferred form of lamp and that such changes as fall within the scope of the appended claims may be made in the construction of the minor details thereof without departure from the 80 spirit of the invention.

Having thus described my invention, what I claim as new and desire to protect by Letters Patent is:

1. In a portable electric lamp, the combination of a hollow foot and stand, a rotatable sleeve on said stand, and projecting into said foot, said sleeve being formed with depending flanges, one of said flanges being formed with a notch, a metal strip depending from 85 said hollow foot into the line of motion of said flanges, to enter said notch of the specific flange upon the rotation of said sleeve for limiting the rotation of the sleeve.

2. A means for opening and closing the 90 electric circuit for a portable electric lamp, of the class described, comprising a hollow foot and stand, a sleeve rotatable on said stand, and projecting into said foot, said sleeve being formed with a pair of depending flanges, one of said flanges being formed with a notch on its lower edge, a contact strip depending from said hollow foot into the line of motion of said flanges, to enter the notch of the said flange upon rotation 95 of the said sleeve, limiting its rotation, another contact strip depending from said hollow foot into the line of motion of said 100

105

flanges, and a contact fastened to the other of said flanges, contacting with last mentioned contact strip, simultaneously with first mentioned contact strip engaging the 5 said notch.

3. A means for opening and closing the electric circuit for a portable electric lamp, of the class described, comprising a hollow foot and stand, a sleeve rotatable on said 10 stand, and projecting it into said foot, said sleeve being formed with a pair of depending flanges, one of said flanges being formed with a notch on its lower edge, a contact strip depending from said hollow foot into 15 the line of motion of said flanges, to enter

the notch of the said flange upon rotation of the said sleeve, limiting its rotation, another contact strip depending from said hollow foot into the line of motion of said flanges, and a pin fastened to the other of 20 said flanges, contacting with last mentioned contact strip, simultaneously with first mentioned contact strip engaging the said notch, both of said contact strips depending from 25 said hollow foot by means of intermediate springs.

In testimony whereof I have affixed my signature.

ALBERT WILD.
